UNITED STATES PATENT OFFICE.

WILLIAM JOHN BROWN, OF WEBSTER CITY, IOWA.

CAR-COUPING.

SPECIFICATION forming part of Letters Patent No. 325,155, dated August 25, 1885.

Application filed March 21, 1885. (No model.)

To all whom it may concern:

Be it known that I, W. J. BROWN, of Webster City, county of Hamilton, State of Iowa, have invented a new and Improved Self-Acting Car-Coupler for Railroad-Cars, of which the following is a specification.

The invention relates to that class of car-couplings in which an arrow-head link is used to press open one or two spring-jaws which then fall in behind the head.

Figure 1 of the drawings is a longitudinal vertical section showing the link held; Fig. 2, a plan view; Fig. 3, a longitudinal section showing the movable jaw held up; and Figs. 4 and 5 are perspective views of the jaws removed from the draw-head.

In the drawings, A represents the draw-head, B the movable jaw, and C the fixed jaw. D is the link, having heads d d at the ends. E is a cam on a shaft, e, which is turned by a hand-lever, E', to lift the spring F, which carries the movable jaw B. The lever E' has a spring, e', fastened thereto and end slotted at the free end, so as to press against the keeper or guide e'', and thus hold the jaw B up or down.

The jaws B C are peculiarly constructed, so as to enable them to perform their functions to the best advantage, and not to be liable to get out of order.

The jaw B has a solid part, b, an opening, b', through which the link-head passes, an open top slot, b'', across which is arranged the pivot for spring F, and a rear projection, b''', by which the link-head is raised in uncoupling.

The jaw C has an upper tenon, c³, on which the jaw B slides, and which works in the aperture b'. c² c² are shoulders or stops for the

sliding jaw B to rest upon when pressed down by spring F. c' is a front flange at the bottom to fit under the part a of the draw-head, and c' is a hole through which passes a screw-bolt fastening, e. The draw-head is suitably grooved to receive these jaws and has a cavity, G, behind them for the link-heads.

The jaw B in its upward movement is liable to cramp and jam in the grooves of draw-head when lifted by an arm which necessarily moves in the arc of a circle. In order to overcome this tendency, I use a spring-arm of flat elastic metal and having an eye, f, at the front end, so that the eccentricity of the motion of jaw B and arm F will be taken up mainly by the yield of the spring. The spring-arm thus performs two functions in uncoupling—namely, to raise the jaw and to neutralize the eccentricity of its own motion.

Having thus described all that is necessary to a full understanding of my invention, what I claim as new, and desire to protect by Letters Patent, is—

1. The sliding jaw B, provided with opening b' and rear projection, b''', in combination with a fixed jaw, C, having tenon c³ and shoulders c² c², whereby said jaw in rising not only unlocks itself from the link but also the fixed jaw by carrying the link-head up above said fixed jaw.

2. The combination of a draw-head having keeper e', the lever E', carrying spring e' near its handle end, and the shaft e, carrying cam E, with the sliding jaw B, as and for the purpose specified.

WILLIAM JOHN BROWN.
